PICKLE CANNING MACHINE

Robert H. Eckart, Corydon, Ind., assignor to Food Packers, Inc., Corydon, Ind., a corporation of Indiana

Application July 31, 1953, Serial No. 371,615

14 Claims. (Cl. 141—78)

The present invention relates in general to container filling and compacting machines, and more particularly to machines for mechanically advancing a plurality of containers and compacting in the same elongated food commodities such as pickles and the like.

An object of the present invention is the provision of novel apparatus for feeding and compacting elongated food commodities into a plurality of intermittently advanced containers.

Another object of the present invention is the provision of novel apparatus for mechanically feeding and compacting elongated food commodities such as pickles and the like into intermittently advanced containers, in erect position within the containers.

Another object of the present invention is the provision of a novel machine for compacting elongated food commodities into intermittently advanced containers of various sizes and shapes.

Another object of the present invention is the provision of a novel machine for compacting elongated food commodities into intermittently advanced containers, wherein the commodities are packed in erect position adjacent the walls of the container under the influence of centrifugal forces applied thereto.

Another object of the present invention is the provision of a novel machine for compacting elongated food commodities into intermittently advanced containers, wherein the elongated commodities are continuously fed in parallel groups of end-to-end aligned commodities simultaneously to a plurality of containers.

Another object of the invention is the provision of a novel machine for advancing and filling containers with elongated food commodities, having means controlling the supply of the commodities to the machine in accordance with the quantity of commodities deposited in the machine.

Other objects, advantages and capabilities of the invention will become apparent from the following detailed description, taken in conjunction with the accompanying drawings, showing only a preferred embodiment of the invention.

In the drawings:

Figure 1 is a front elevation of a machine embodying the present invention.

Figure 2 is a side elevation of the machine viewed from the left-hand side of Figure 1 and in which parts of the feed drum are broken away and parts of the feed and container supporting mechanism are illustrated in section;

Figure 3 is a rear elevation of the machine;

Figure 4 is a fragmentary section view of a portion of the machine taken along the lines 4—4 of Figure 2;

Figure 5 is a fragmentary section view of the spring idlers and associated portions of the machine taken along the lines 5—5 of Figure 2;

Figure 6 is a section view taken along the lines 6—6 of Figure 2 and illustrating the mechanism for tamping the containers;

Figure 7 is a fragmentary transverse section view of the container chucks taken along the lines 7—7 of Figure 2; and

Figure 8 is a vertical transverse section taken along the lines 8—8 of Figure 6.

The present invention relates in general and is directed to a machine for automatically filling jars or other containers of various sizes with pickles or other elongated food commodities. To this end the machine employs means for intermittently advancing a plurality of containers in commodity-receiving relation to continuous supply means for the commodities, means for feeding the articles one by one to a plurality of the intermittently advanced containers in simultaneous relation, means for alternately rotating the containers a number of turns in one direction at high speed and then a number of turns in the reverse direction during feeding of the commodities to the container, and means for vibrating the containers along their axes during rotation of the same, the latter two means serving to pack the elongated commodities in erect position against the walls of the container through centrifugal force and tamping action. Additional means are incorporated in the system to control the supply of commodities to the supply means in accordance with the quantities of commodities already deposited in the supply means, and means associated with the endless conveyor means for receiving and holding containers of various sizes and shapes.

The invention will be more fully understood from the following detail description, referring to the drawings wherein like reference characters designate corresponding parts throughout the several figures. The machine of the present invention, which in the preferred embodiment to be now described is specifically designed for packing jars with pickles, is indicated generally by the reference character 10, and is provided with an intermittent conveyor generally indicated at 11 for supporting and advancing the container jars, indicated at 12, the conveyor 11 being supported on a table-like machine support 13. To this end, the conveyor 11 comprises a driven sprocket 14 and an idler sprocket 15 disposed on opposite sides of the supporting table 13 and journaled for rotation in a plane rearwardly and upwardly inclined to the horizontal on a driven shaft 16 and idler shaft 17, respectively, journaled in suitable bearings 18 carried by laterally projecting elements 13a extending from and forming a part of the supporting table 13. Rigidly fixed on the driven shaft 16 is a ratchet 19 cooperating with a pawl and pawl carrier 20 journaled on the driven shaft 16 for rotation about the axis of said shaft. The pawl assembly 20 is pivotally coupled through an adjustable connecting rod 21 to a crank arm 22 fixed to the shaft 23 of a gear reduction unit 24, which in turn is driven by a belt and pulley coupling 25 with the armature shaft 26a projecting from an electric motor 26.

Trained about the driven sprocket 14 and idler sprocket 15 is an endless chain 27 comprising link units 28 consisting of a spaced pair of elongated parallel link elements 28a, 28b, interspaced by link units 29 consisting of an elongated link element 29a extending between and pivotally coupled to the spaced link elements 28a, 28b, of both adjacent link units 28, and carrying spacer blocks 29b whose outer faces are in coplanar relation with the outer faces of the link elements 28a, 28b. Both link units 28 and 29 are provided with apertures 30 extending entirely therethrough for supporting individual container-gripping chuck assemblies 31.

The chuck assemblies 31, as illustrated in Figures 2, 6 and 7, each consist of an upwardly opening cylindrical receptacle 32 having cylindrical side walls 33 preferably formed of sheet material supported from a circular base 34 having a downwardly projecting abutment disc por-

tion 34a. Within the cylindrical receptacle 32 is a rubber liner 35 normally disposed in a rectangular path within the container by means of four binding strips 36 extending from the base 34 parallel to the axis of the receptacle 32 to the lip of the receptacle and riveted or otherwise fixed to the side walls 33 thereof at diametrically opposed points. The rubber liner therefore forms a circle at the top of the cylinder which graduates into a square cross section approximately two inches below, the sides of the square corresponding to chords of the circular cross section of the receptacle, which resiliently grip the containers 12 to be inserted therein and firmly hold the same in the chuck receptacle 32.

Projecting downwardly from the base 34 of the chuck receptacle 32 is a shaft 37 to be disposed through the apertures 30 in the links of the endless chain 27. A pulley 38 is keyed to the shaft 37 at a point below the links of the endless chain, which pulley 38 is continuously biased to its uppermost limit of travel by a coil spring 39 bearing at one end against the pulley 38 and its other end against a cap 40 fixed to the lower end of the shaft 37.

As will be apparent from an inspection of Figures 1, 2 and 3 of the drawing, the containers 12 carried by the upper reach of the endless chain 27 extend through the hollow bore of a feed drum 41, by which the pickles are gravity-fed in parallel groups of end-to-end aligned pickles into the upwardly opening mouths of the containers located within the bore of the drum. The drum 41 is continuously rotated in a counter-clockwise direction as viewed in Figure 2, and to this end rests on a pair of laterally spaced endless belts 42 trained about idler pulleys 43 and driven pulley 44 arranged at opposite sides of the center of the drum 41. The driven pulleys 44 are each fixed on a transverse driven shaft 45 journaled in suitable bearings 46, one end of the shaft 45 projecting beyond one of the bearings 46 and having a large pulley 47. A continuous driving torque is applied to the pulley 47 to rotate the driven pulleys 44 and the drum 41 by means of a V-belt 48 trained about the pulley 47 and about a driving pulley 49 mounted on a transverse main drive shaft 50 having a large pulley 51 intercoupled through a V-belt 52 with a drive pulley 53 on the drive shaft 26a of the electric motor 26.

The drum 41 is formed of a cylindrical wall 55 bounded by diverging annular side walls 56, between which a plurality of vane assemblies 57 extend. The vane assemblies each comprise a radial supporting plate 58 welded or otherwise fixed to the inner surface of the cylindrical wall 55, to the innermost end of which a pivoted vane plate 59 is hinged by hinges 60. A tripping rod or finger 61 is welded to the hinged vane plate 59 adjacent one lateral edge thereof and projects inwardly of and beyond the adjacent annular side wall 56 to strike a fixed tripping lug 62 carried by one of two fixed annular sector plates 63 disposed outwardly of each side of the drum 41 and supported at their lower ends upon rigid uprights 13b extending from the supporting table 13. A corrugated chute 64 of substantially the width of the vane assemblies 57 is disposed inside the drum 41 with its outer end adjustably supported adjacent the tripping lug 62 at the upper end of the annular sector plates 63 by means of bolts 65 on the chute 64 extending through slots 63a in the sector plates 63. The corrugated chute 64 is provided, in the preferred embodiment, with six side-by-side concave downwardly-converging troughs 66 terminating adjacent the upwardly opening mouths of the containers 12 supported by the chuck assemblies 31 within the drum 41 and the chute 64 is designed to be oscillated about its pivotal coupling with the sector plate 63 by the bolt 65 and slots 63a by means of a rocker arm 67 pivotally coupled at 68 to the lower end of the chute 64 and slidably supported in a bearing 69 through which the rocker arm 67 projects fixed to the supporting table 13. The portion of the

rocker arm 67 projecting below the bearing 69 is provided with a coil spring 70 disposed between the bearing 69 and an annular flange 67a on the rocker arm to urge the rocker arm downwardly, and with a roller or cam follower 71 bearing upon a cam 72 mounted on a transverse cam shaft 73 which also carries a pulley 74 driven by means of a V-belt 75 trained around the same and about a pulley 76 on the main drive shaft 50.

Pickles are gravity fed to the drum 41 by means of any conventional conveyor means, preferably by an endless belt conveyor, generally indicated at 77, mounted on a cantilever arm and projecting into the hollow of the drum 41; the free end of the endless belt conveyor 77 terminating approximately midway of the sides 56 of the drum 41 so that the pickles drop off of the end of the conveyor 77 into the receptacles defined between successive vane assemblies 57 and the divergent annular side walls 56 of the drum.

Mechanism is provided to spin the container gripping chucks 32 located within the drum 41 a plurality of turns at high speed in one direction and a plurality of turns in the reverse direction during the interval between intermittent advancement of the chucks. This mechanism includes a double V-belt 78 guided alongside the series of pulleys 38 of the chuck assemblies 31 within the drum 41 by means of a pair of idler pulleys 79 mounted adjacent opposite sides of the drum, for example on uprights 13c of the supporting table 13. The double V-belt pulley 78 is trained over the idler pulleys 79 and a plurality of idler pulleys 80 journaled in the lower portion of the supporting table 13, and thence over a large radius oscillatory drive pulley 81 fixed on a shaft 82 which also carries a small radius pinion 83. The small radius pinion 83 cooperates with a rack 84 pivotally coupled at one end thereof to a crank arm 85 mounted on the shaft 23 of the gear reduction unit 24 and extending in diametrically opposed relation to the crank arm 22 to which pawl-actuating connecting rod 21 is pivoted. By this arrangement, the oscillatory drive pulley 81 is rotated first in one direction and then in another direction to drive the double V-belt 78 and spin the chuck assemblies 31 during a full cycle of movement of the rack 84 comprising a forward and a reverse stroke during the period between successive actuations of the pawl assembly 20 to drive the ratchet 19 and driven sprocket 14.

The portion of the double V-belt pulley 78 extending between the idler pulleys 79 is resiliently urged into frictional driving contact with the pulleys 38 of the chuck assemblies 31 by means of spring loaded idler pulleys 86 bearing against the beveled portion of the belt 78 opposite that in contact with the chuck pulleys 38, the spring loaded idler pulleys 86 being freely journaled on pivoted supporting arms 87 which are spring biased toward the belt 78 by means of compression springs 88 in compressed condition between the pivoted supporting arms 87 and a wall 89 of an open ended idler pulley housing 90 surrounding the group of idler pulleys 86, the belt 78, and the portions of the chuck assemblies 31 projecting below the links of the endless chain 27.

To assist in guiding and stabilizing the endless chain 27 during its movement through the feed drum 41, the housing 90 is provided with a wall 91 opposite and parallel to the wall 89, both the walls 91 and 89 extending to a point aligned approximately with the medial plane 65 of the portion of the endless chain 27 extending through the drum and each having guide flanges 92 extending toward the chain 27 and into grooves formed in the opposite sides thereof by reason of the link elements 28a and 28b being of greater width than link elements 29a.

Means are also provided for jogging the chuck assemblies 31 and the containers 12 held therein in the direction of the axes of the chuck assemblies 31 during spinning of the same comprising a jogging bar 93 extending transversely through the drum 41 and having oppositely beveled ends 93a, the jogging bar 93 being positioned

to engage the caps 40 on the lower end of the chuck assembly shafts 37 and cam the same upwardly into supported relation on the bar 93 when the chuck assemblies are within the drum 41. The ends of the jogging bar 93 are each supported by control rods 94 extending through and supported for rectilinear movement by brackets 95 on the supporting table uprights 13b. The lower ends of the control rods 94 are pivotally coupled to arms 96, which in turn are pivotally supported on the table 13. The lower ends of the control rods 94 also carry cam followers or rollers 97 bearing against cams 98 fixed to a transverse shaft 99 journaled for rotation on the horizontal supporting surface of the table 13, which shaft carries a pulley 101 drivingly coupled by a V-belt 102 with a pulley 103 on the main transverse drive shaft 50.

Means are also provided for selectively terminating feeding of the pickles to the drum 41 for an appropriate period of time when the weight of pickles carried by the drum 41 exceeds a preselected limit. To this end, the bearings 46 supporting the shaft 45 carrying the driven pulleys 44 for the endless belt 42 on which the drum is supported are mounted on elongated blocks 105 which are pivotally supported at the end supporting the bearings 46 on the table 13, as indicated at 106. A transverse shaft 107 supporting the idler pulleys 43 about which the belts 42 are trained is journaled in bearings 108 which in turn are supported on the elongated blocks 105 adjacent their free ends, these ends of the blocks 105 being resiliently supported by a compression spring and supporting collar 109 and by a micro switch 110. The micro switch may be normally maintained in open position by adjusting the tension of the spring support 109 to support the elongated blocks 105 in elevated position for normal loads of pickles in the drum 41 so that the force of the spring 109 will be overcome sufficient to actuate the micro switch 110 only when the weight of pickles in the drum 41 exceeds a preselected level. The micro switch 110 will preferably control the electrical supply to the coil of a normally closed relay or like device, the contacts of which are in series circuit relation with the energizing circuit of an electric motor or other driving means for the endless conveyor belt 77. Thus so long as the micro switch 110 is closed, the contacts of the relay will be open-circuited, terminating driving of the endless conveyor belt 77.

As illustrated in Figures 1 and 2, an inclined chain guide strip 111 is provided adjacent the forwardmost reach of the endless chain 27 to be received in the groove defined between the link elements 28a and 28b and guide the endless chain 27 between the sprockets 14 and 15.

The operation of the above device is substantially as follows. Assuming jars or other pickle containers 12 are frictionally seated in the receptacles 32 of the chuck assemblies 31, rotation of the shaft 23 and crank arm 22 of the gear reduction unit 24, driven by the motor 26 and its output shaft 26a, imparts reciprocal motion to the connecting rod 21 and pawl assembly 20, to oscillate the pawl 20 about the driven shaft 16. The connecting rod 21 is adjusted to an appropriate length such that the pawl 20 engages and drives the teeth of the ratchet 19 only during the portion of rotation of the drive shaft 23 and crank arm 22 during which no drive is imparted to the oscillatory drive pulley 81 by the rack 84 and pinion 83. The length of the stroke of the pawl 20 is also adjusted so that the step by step drive imparted to the shaft 16 and driven sprocket 14 is just sufficient to advance one of the chuck assemblies 31 and containers 12 from one of the concave troughs 66 of the feed chute 64 to the next adjacent concave trough.

During the interval between successive actuation of the sprocket 19 by the pawl 20, the oscillatory drive pulley 81 is rotated a number of turns at high speed in one direction and then a number of turns in the opposite

direction through the rack 84 engaging the pinion 83 and driven by the crank arm 85 on the shaft 23 of the gear reduction unit 24. This reciprocal driving action of the oscillatory driving pulley 81 is transmitted through the double V-belt 78 to the pulleys 38 of the chuck assemblies 31 located within the drum 41, the belt being urged into intimate frictional engagement with the pulleys 38 located within the drum 41 by means of the spring loaded idler pulleys 86 pivotally supported on the arms 87.

Also, the chuck assemblies whose caps 40 are resting on the jogging bar 93 are jogged along their axes continuously during the operation of the machine through the jogging motion imparted to the jogging bar 93 through their control rods 94 and cam followers 97 resting on the cams 98. The cam shaft 99 supporting the cams 98 is in turn continuously driven through the V-belt 102 trained about the pulley 101 on the cam shaft 99 and a pulley 103 on the main drive shaft 50 which is continuously driven by the belt 52 trained about its pulley 51 and the pulley 53 on the armature shaft 26a of the motor 26. The jogging action arising from the movement of the bar 93 occurs not only at the end of the up-stroke of the bar 93 but also at the down-stroke. This arises by virtue of the fact that a shoulder on the pulley 38 extends to a point near the lower surface of the link elements 28a and 28b and is disposed to abut a hardened washer 37a near the end of the up-stroke of the bar 93, and the projecting portion 34a of the chuck 32 is disposed to engage a hardened washer 37b and jar the chuck near the end of the down-stroke of the jogging bar 93.

Jogging action is also applied continuously to the lower end of the feed chute 64 through the rocker arm 67 supporting the same and having a cam follower 71 on the lower end thereof riding on the continuously driven cam 72 on shaft 73, the shaft 73 being driven by the belt 75 trained about the pulley 74 on the shaft 73 and a pulley 76 on the main drive shaft 50. Such jogging of the chute 64 serves to align the pickles in end to end relation in the plurality of concave troughs 66 and feed them under the influence of gravity into the upwardly opening mouths of the containers 12 disposed adjacent the lower end of the chute 64 in alignment with the troughs.

Pickles which are dumped from the end of the endless conveyor 77 into the bottom of the drum 41 are conveyed to the trough in the following manner. Since the drum 41 is rotated in a counter-clockwise direction as viewed in Figure 2, the pickles in the portion of the drum 41 lying between two successive vane assemblies 57 are elevated into juxtaposition with the upper end of the trough 64 by the lowermost of the vane assemblies between which the pickles lie. As the pivoted vane 59 reaches a point of alignment with the upper end of the trough 64, the vane tripping finger 61 engages the fixed tripping lug 62 projecting inwardly from the fixed annular sector plate 63 to tilt the pivoted vane 59 about the hinge 60 as the drum 41 continues to rotate and transfer all the pickles in that sector of the drum to the chute 64.

It will be apparent that any pickles which are barred admission to the containers 12 by reason of misalignment or because of contact with pickles already in the container will merely fall by the containers and chuck assemblies into the lower portion of the drum 41 and be elevated into position to be fed to subsequent containers. It will further be apparent that the jogging of the chuck assemblies assists materially in compacting the pickles toward the bottom of the containers 12, and that the spinning of the containers in first one and then a reverse direction during feeding of the same tends to centrifugally compact the pickles toward the outer walls of the containers and aligns them in erect position about the axis of the container. By spinning the containers and chuck assemblies in opposite directions, the slight tilting of pickles which would arise from spinning the chucks in

one direction only is avoided and the pickles are forced into more perfect erect alignment.

By the above construction, therefore, a mechanism is provided which effectively fills and packs pickle containers with pickles in a certain desired alignment without necessitating manual feeding of pickles to the containers except in very rare instances, thus drastically reducing the labor heretofore required in packaging pickles.

While but one particular embodiment of the invention has been particularly shown and described, it is apparent that various modifications may be made in the invention without departing from the spirit and scope thereof, and it is desired, therefore, that only such limitations shall be placed thereon as are imposed by the prior art and are set forth in the appended claims.

What is claimed is:

1. A machine for filling containers with food commodities and the like comprising a food commodity supply station, means for intermittently advancing a plurality of containers sequentially by said station in commodity-receiving relation thereto, and means for rapidly spinning the containers adjacent said station a plurality of turns forwardly and reversely about an axis extending through said containers during the period between intermittent advancement of said containers.
2. A machine for filling containers with food commodities and the like comprising a food commodity supply station, means for intermittently advancing a plurality of containers sequentially by said station in commodity-receiving relation thereto, means for rapidly spinning the containers adjacent said station a plurality of turns in one direction and a plurality of turns in a reverse direction about an axis extending through said containers during the period between intermittent advancement of said containers, and means for jogging the containers adjacent said station in the direction of said axis continuously during spinning of the same.
3. A machine for filling containers with elongated food commodities such as pickles and the like comprising a food commodity supply station, means for intermittently advancing a plurality of upwardly opening containers sequentially by said station in commodity-receiving relation thereto, and means for spinning the containers adjacent said station at high speed a plurality of turns in one direction and a plurality of turns in a reverse direction about the axes of said containers during the period between intermittent advancement of said containers.
4. A machine for filling containers with elongated food commodities such as pickles and the like comprising a food commodity supply station, means for intermittently advancing a plurality of upwardly opening containers sequentially by said station in commodity-receiving relation thereto, and means adjacent said station for spinning the adjacent containers about their medial axes at high speed a plurality of turns in one direction and a plurality of turns in a reverse direction during the period between intermittent advancement of said containers.
5. A machine for feeding and compacting food commodities into containers comprising a food commodity supply station, means for intermittently advancing a plurality of open containers sequentially by said station in commodity-receiving relation thereto, means for feeding food commodities from said supply station into the containers adjacent the same, means for spinning said containers at high speed in one direction and then in the reverse direction about the axes of said containers intermediate intermittent advancement of said containers, and means for jogging said containers in the direction of their axes continuously during spinning of said containers.
6. A machine for feeding and compacting elongated food commodities into containers comprising a food commodity supply station, means for intermittently advancing a plurality of open containers sequentially by said station in commodity-receiving relation thereto, means for gravity feeding food commodities in end-to-

end aligned relation from said supply station into the containers adjacent the same, means for spinning said containers at high speed in one direction and then in the reverse direction about the axes of said containers intermediate intermittent advancement of said containers to centrifugally urge the food commodities in said containers in erect position outwardly of the same, and means for jogging said containers in the direction of their axes continuously during spinning of said containers.

7. A machine for feeding and compacting elongated food commodities such as pickles and the like into containers comprising a food commodity supply station, means for intermittently advancing a plurality of upwardly opening containers sequentially by said station in commodity-receiving relation thereto including rotatably supported chuck means for frictionally gripping each container, means for feeding food commodities in parallel groups of end-to-end aligned commodities from said supply station simultaneously into a plurality of the containers adjacent the same, and means engaging said chuck means only when the same are adjacent said supply station for spinning each of said chuck means operatively engaged thereby at high speed in one direction and then in the reverse direction about the axis of each of said engaged chuck means during each period intermediate intermittent advancement of said containers to centrifugally urge the food commodities in said containers outwardly of the same.
8. A machine for feeding and compacting elongated food commodities such as pickles and the like into containers comprising a food commodity supply station, means for intermittently advancing a plurality of upwardly opening containers sequentially by said station in commodity-receiving relation thereto including rotatably supported chuck means for frictionally gripping each container, means for feeding food commodities in parallel groups of end-to-end aligned commodities from said supply station simultaneously into a plurality of the containers adjacent the same, means frictionally engaging said chuck means only when the same are adjacent said supply station for spinning said engaged chuck means at high speed in one direction and then in the reverse direction about the axis of each of said engaged chuck means during each period intermediate intermittent advancement of said containers to centrifugally urge the food commodities in said containers outwardly of the same, and means engaging said chuck means only when the same are adjacent said supply station for jogging said chuck means in the direction of their axes continuously during spinning of said chuck means.
9. A machine for feeding and compacting elongated food commodities such as pickles and the like into containers comprising inclined chute means having a plurality of parallel guide troughs therein for guiding food commodities transferred thereto in parallel groups of end-to-end aligned commodities, rotary means for elevating the commodities to a position to be gravity discharged onto the uppermost portion of said chute means, means for intermittently advancing a plurality of upwardly opening containers sequentially by the lowermost end of said chute means in commodity receiving relation thereto, means for spinning said containers at high speed in one direction and then in the reverse direction about the axes of said containers during each period intermediate intermittent advancement of said containers, and means for jogging said containers in the direction of their axes continuously during spinning of said containers.
10. A machine for feeding and compacting elongated food commodities such as pickles and the like into containers comprising inclined chute means having a plurality of parallel guide troughs therein for guiding food commodities transferred thereto in parallel groups of end-to-end aligned commodities, rotary means for elevating the commodities to a position to be gravity discharged onto the uppermost portion of said chute means,

endless conveyor means having chuck means rotatably carried thereby for frictionally gripping and supporting a plurality of containers, means driving said endless conveyor means for intermittently advancing said containers to sequentially dispose a plurality of said containers in commodity-receiving relation relative to said chute means, means for vibrating said chute means to gravity feed the commodities along said chute and transfer the same into said containers, and means engaging said chuck means only when the same are adjacent said chute means for spinning said chuck means at high speed in one direction and then in the reverse direction about the axis of said chuck means during each period intermediate intermittent advancement of said containers to centrifugally urge the food commodities in said containers in erect position outwardly of the same.

11. A machine for feeding and compacting elongated food commodities such as pickles and the like into containers comprising a continuously rotated, open-ended drum having internally opening receptacle portions therein for receiving and elevating food commodities supplied thereto to a discharge station, inclined chute means located internally of said drum and disposed adjacent said discharge station to receive food commodities from said drum, said chute means having a plurality of parallel guide troughs for receiving and guiding the commodities transferred thereto in end-to-end aligned relation along parallel paths, endless conveyor means extending through said drum and having chuck means rotatably supported thereon for frictionally gripping and supporting a plurality of containers, driving means for said endless conveyor means for intermittently advancing said chuck means to successively dispose groups of said containers in commodity-receiving relation with said chute means, means for vibrating said chute means to gravity feed the commodities thereon down the incline of said chute means and into said containers, and means engaging said chuck means only when the same are adjacent said chute means for spinning said chuck means at high speed in one direction and then in the reverse direction about the axis of said chuck means intermediate intermittent advancement of said containers to centrifugally urge the food commodities in said containers in erect position outwardly of the same.

12. A machine for feeding and compacting elongated food commodities such as pickles and the like into containers comprising a continuously rotated, open-ended drum having internally opening receptacle portions therein for receiving and elevating food commodities supplied thereto to a discharge station, inclined chute means located internally of said drum and disposed adjacent said discharge station to receive food commodities from said drum, said chute means having a plurality of parallel guide troughs for receiving and guiding the commodities transferred thereto in end-to-end aligned relation along parallel paths, endless conveyor means extending through said drum and having chuck means rotatably supported thereon for frictionally gripping and supporting a plurality of containers, driving means for said endless conveyor means for intermittently advancing said chuck means to successively dispose groups of said containers in commodity-receiving relation with said chute means,

means for vibrating said chute means to gravity feed the commodities thereon down the incline of said chute means and into said containers, means frictionally engaging said chuck means only when the same are adjacent said chute means for spinning said chuck means at high speed in one direction and then in the reverse direction about the axis of said chuck means intermediate intermittent advancement of said containers to centrifugally urge the food commodities in said containers outwardly of the same, and means engaging said chuck means only when the same are adjacent said chute means for jogging said chuck means in the direction of their axes continuously during spinning of said chuck means.

13. In a machine for feeding and compacting elongated food commodities such as pickles and the like into containers, the combination recited in claim 11 wherein said open-ended drum comprises a cylindrically curved wall of sheet material bounded at each lateral edge by diverging annular side wall portions defining therebetween a commodity receiving trough, and a plurality of transverse vane assemblies are provided within said trough section and extending between said side walls, said vane assemblies comprising a fixed transverse vane member fixed to said cylindrically curved wall and a pivoted vane wall hinged to said fixed vane wall and having a shape conforming substantially to the transverse cross section of said trough, and wherein an inwardly projecting arm is rigidly fixed to said pivoted vane wall and a tripping lug is fixedly positioned on said machine to be engaged by said projecting arm during rotation of said drum to tilt said pivoted vane wall about its hinged connection with said fixed vane wall.

14. In a machine for feeding and compacting elongated food commodities such as pickles and the like into containers, the combination recited in claim 7 wherein said means for spinning said chuck means comprises a driven pulley, endless belt means trained over said pulley and frictionally engaging said chuck means, a continuously driven shaft having a pair of oppositely radiating crank arms thereon, and rack and pinion means intercoupling said driven pulley with one of said crank arms whereby the reciprocal motion imparted to the rack drives said driven pulley a number of turns in one direction and then a number of turns in the reverse direction, and wherein said means for advancing said containers comprises a driving sprocket, shaft means for said sprocket, a ratchet fixed to said shaft means, pivoted pawl means operatively associated with said ratchet, and connecting rod means pivotally intercoupling said pawl means with the other of said crank arms, said pawl means being actuated in out-of-phase relation with rotation of said driven pulley to drive said sprocket and advance said containers intermediate successive spinning of said containers in opposite directions.
